Attorney

UNITED STATES PATENT OFFICE.

OLIVER ADCOCK, OF ROCKY FORD, COLORADO.

SLUICE BOX OR RIFFLE.

Application filed March 24, 1926. Serial No. 97,046.

My present invention relates to improvements in means for separating precious metals by washing or analogous methods, and aims to provide a novel construction by 5 which a greater recovery of the precious minerals may be secured in a more rapid and expeditious manner than is possible with anything of which I am aware.

The invention includes the novel construction hereinafter described and particularly defined in the appended claim.

In order that the invention may be better understood I have appended hereto drawings illustrating what I at present consider 15 the preferred embodiment of my invention. While these show the invention as embodied in a sluice box or riffle designed to be mounted upon a suitable frame, either stationary or oscillating as desired, it will be understood that it is capable also of being embodied in a hand operated device.

In these drawings:—

Figure 1 is a plan view of the sluice box or riffle.

Fig. 2 is a side elevation.

Fig. 3 is a section on line 3—3 of Fig. 1.

Fig. 4 is a partial section on line 4—4 of Fig. 1.

Referring by reference characters to this 20 drawing, the numeral 1 designates a substantially trough-shaped member, preferably constructed of sheet metal and having a substantially plane bottom 1^a and end flanges 1^b by which it may be bolted or otherwise secured to a suitable wooden frame (not shown). This bottom is provided with a plurality of pockets 2 which are of inverted

cone shape and are preferably arranged in a plurality of rows, as shown. Extending transversely of the sluice box are a plurality 40 of rows of baffles 3 of less height than the sluice box, and which extend across or bisect the open mouths of the pockets. Preferably the baffles are set substantially perpendicular to the plane of the bottom, and preferably 45 also the cone shaped pockets have their axes inclined to planes perpendicular to the plane of the bottom so that when the riffle or sluice box is supported in inclined position to provide for the flow of the water or 50 other fluid bearing the mineral to be separated, the axes of the pockets will be perpendicular.

Having thus described my invention, what I claim is:—

A riffle comprising a trough having a plane bottom and upstanding parallel sides, said bottom having a plurality of rows of pockets therein between said sides and extending from the inlet end to the outlet end 60 of said trough, said pockets being of inverted cone shape and having their axes similarly inclined toward the inlet end of the trough, whereby each pocket is intersected by the bottom of the trough at the same angle, and 65 a baffle perpendicular to the bottom and extending across the open mouths of each row of pockets laterally of the trough, whereby the pockets of each row have their axes similarly inclined to the plane of their coacting baffle.

In testimony whereof, I affix my signature.

OLIVER ADCOCK.
